WINDOW VENTILATOR

Filed April 14, 1930

Fig. 1.

J. D. Green, INVENTOR

BY *Victor J. Evans*

ATTORNEY

WITNESS -

UNITED STATES PATENT OFFICE

LEONARD D. GREEN, OF ERIE, PENNSYLVANIA

WINDOW VENTILATOR

Application filed April 14, 1930. Serial No. 444,227.

This invention relates to new and useful improvements in ventilators for windows and has for the primary object, the provision of a device of the above stated character which 5 may be applied to or form part of a window sash either constructed from wood or metal or of the sliding or swinging types and which will permit a person to easily and quickly ventilate a room without a direct draft. 10 Another object of this invention is the provision of means whereby the ventilator may be opened and closed as desired to control the amount of air to the room according to the desires of the user. 15 A further object of this invention is the provision of means to prevent direct draft or flow of air through the ventilator when the air control means is partly or fully open.

A further object of this invention is the 20 provision of an ornamental screen to be placed inside of the ventilator to prevent the entrance of foreign matter along with the air and which will produce a pleasing appearance to the device from any point within the room.

25 A still further object of this invention is the provision of a ventilator of the above stated character which will be simple, durable and efficient, and which may be manufactured and sold at a comparatively low 30 cost.

With these and other objects in view as will 35 become more apparent as the description proceeds, the invention consists in certain novel features of construction, combination and arrangement of parts as will be hereinafter more fully described and claimed.

For a complete understanding of my invention reference is had to the following 40 description and accompanying drawings, in which:

Figure 1 is a fragmentary front elevation illustrating a window with a ventilator applied thereto and constructed in accordance 45 with my invention.

Figure 2 is a fragmentary transverse sectional view illustrating the ventilator and showing in dotted lines the air control in an open position.

50 Figure 3 is a fragmentary front elevation

illustrating the actuating means for the air control.

Figure 4 is a longitudinal sectional view illustrating the device.

Figure 5 is a fragmentary sectional view 55 illustrating a modified form of my invention.

Referring in detail to the drawings, the numeral 1 indicates a casing having the inner and outer side walls open and is positioned in a window sash 2 as clearly shown in Figures 1 and 2 of the official drawings. The sash 2 may be of any well known type and constructed from any material now employed in the making of such and is provided with an elongated opening to receive 60 the casing 1 by cutting away the glass 3 and strips 4 so that the glass and strips rest upon the top wall 5 of the casing 1 as clearly shown in Figure 2. The end walls of the casing are angularly bent and secured to the window 65 sash 2 as shown at 6. A skeleton frame 7 overlying the inner side wall of the casing is secured to the sash 2 as shown at 8. The frame 7, is provided with a plurality of elongated slots and may be of any ornamental 70 design to provide an attractive appearance to the device from a point within the room.

An auxiliary frame carrying wire mesh 9 is positioned in rear of the frame 7 to close the elongated slots and is secured therein by clips 75 80 10 and 11 engaging portions of the inner side wall of the casing. The clips 10 and 11 are so arranged that the auxiliary frame carrying the screen 9 may be moved upwardly to disengage the clip 11 from the casing 1 and 85 swung outwardly sufficiently to permit the clip 10 to be disengaged from the casing thereby permitting the screen to be cleaned of foreign matter which may have adhered thereto.

The top wall of the casing 5 is off-set downwardly to form a seat for the glass 3 as clearly shown in Figure 3. The outer side wall of the casing 1 adjacent the upper edge thereof is bent inwardly and upwardly to form a 90 flange 12 to receive a correspondingly shaped flange 13 formed on the upper edge of a ventilation control plate 14 thereby establishing a hinge connection between said plate 14 and the casing 1. The lower edge of the plate 100

14 has a spring catch 15 formed thereon to engage over a bead 16 formed on the casing 1 when the plate 14 is in a closed position to prevent accidental swinging of the plate 5 due to the wind striking against the plate. The bead 16 forms a seat to receive a portion of the lower rail of the sash 2 as shown in Figure 2 thereby aiding in retaining the casing 1 in position.

10 An operating lever 17 is secured to the inner face of the plate 14 and extends through a slot 18 in the frame 7 and is provided at its free end with a suitable finger grip 19. A lug 20 is carried by the lever 17 to engage in any 15 one of a plurality of notches 21 formed in the plate 7 for holding the plate 14 in various adjusted positions.

A wind deflector is positioned within the casing 1 and comprises a plate 22 secured to the top and bottom walls of the casing 1 and is provided with a plurality of struck-out portions 23 that incline upwardly and outwardly from the plate 22 to provide wind deflecting elements which will prevent the air from passing directly through the casing 1 with too great a volume.

In operation, when desiring to ventilate a room without the necessity of opening the window sash 2, the lever 17 is moved downwardly swinging the control plate 14 outwardly consequently permitting air to pass through the casing into the room in the amount desired. The air passing through the casing is deflected upwardly by the portions 23 of the plate 22 and prevents a direct draft into the room.

Referring to my modified form of invention, the casing 1 may have the top wall 24 formed as shown in Figure 5, to engage a wooden strip 25 which is the lower portion of a wooden window sash, it being understood that the lower portion of the window sash is cut to form a slot to receive the casing 1.

15 While I have shown and described the preferred embodiment of my invention, it will be understood that minor changes in construction, combination and arrangement of parts may be made without departing from the spirit and scope of the invention as claimed.

Having thus described the invention what I claim is:

55 1. A ventilator for windows comprising a
casing associated with a window sash and
having the sides thereof open, an air control
plate hinged to said casing for closing one
side thereof, an ornamental and slotted plate
80 for closing the other side of said casing and
having a slot, an operating lever secured to
the air control plate and extending through
said slot, said slotted and ornamental plate
having a plurality of notches, a lug formed
65 on said lever and adapted to engage in any

one of said notches to hold the air control plate in various adjusted positions.

2. A ventilator comprising a casing including top, bottom and end walls, a screened plate closing one side of the casing, said top wall at one side edge bent downwardly, inwardly and upwardly to provide a hinge section, a closure for the other side of the casing and having one edge bent to provide a hinge section to engage the first mentioned hinge section, a control connected to the closure and extending through the screened plate for opening and closing the closure, said bottom wall having one edge bent to provide a bead, and said closure grooved to receive the bead when in a closed position. 70 75 80

In testimony whereof I affix my signature.
LEONARD D. GREEN.
